A. H. FOX AND A. W. LENDEROTH,
RAILROAD CONTROLLING DEVICE,
APPLICATION FILED MAY 3, 1919.

1,371,675.

Patented Mar. 15, 1921.

UNITED STATES PATENT OFFICE.

AUSTEN H. FOX, OF NEW YORK, AND ARNOLD W. LENDEROTH, OF STAPLETON, NEW YORK.

RAILROAD CONTROLLING DEVICE.

1,371,675.

Specification of Letters Patent.

Patented Mar. 15, 1921.

Application filed May 3, 1919. Serial No. 294,418.

To all whom it may concern:

Be it known that we, AUSTEN H. FOX and ARNOLD W. LENDEROTH, both citizens of the United States, residing at, respectively, New York, county and State of New York, and Stapleton, county of Richmond, and State of New York, have invented certain new and useful Improvements in Railroad Controlling Devices, of which the following is 10 a full, clear, and exact description.

In a number of patents heretofore granted to us we have shown and described railway signaling or controlling devices in the form of small boxes or casings supported 15 back of a car wheel in close proximity to a track rail, and more particularly in Patent No. 1,298,029, dated March 25, 1919, we have shown an apparatus of this kind in which a straight magnetic core was provided with 20 two movable feet or pole pieces which being similarly magnetized tended to repel each other and to normally separate, but which by the attractive effect of the steel rail were drawn together, the movements of the feet 25 due to attractive or repulsive effects being utilized to operate suitable circuit controllers, signals or other devices on the car or locomotive.

Our present invention is an improvement 30 in devices of this class and has for its immediate objects to provide a better and more efficient form of apparatus of this general character, but more especially to secure a better and more dependable action or operation of the working parts under such conditions as are likely to be encountered in general railway practise.

In the forms of apparatus heretofore designed by us the parts have been generally 40 so constructed and related that the car wheel formed part of the magnetic circuit established or maintained through the controlling magnet and armatures, and this is one feature which in our present construction 45 we have sought to avoid. For this purpose we use a longer casing, which is supported in fixed relation to the rail usually by connection with the equalizer of the truck, between the two wheels of a truck, and which 50 comprises a magnetic circuit with a consequent central pole and two end poles of the opposite sign, whereby the path for the magnetic lines will be directly to and from the rail and the three poles of the controlling device within the casing or its walls.

Another feature of improvement in the device upon which the present application is based is the absence of all stops to limit the lateral movement of the movable poles and such construction and arrangement of 60 the latter that their relations to one another are not affected by the lateral motion of the car truck, but only by the magnetic conditions of the rail or armature acting upon the poles.

Other features of novelty and utility of our improved mechanism will be more fully set forth in the accompanying specification.

In the drawings hereto annexed—

Figure 1 is a central vertical longitudinal 70 section of the complete controller.

Fig. 2 is a longitudinal section of a portion of the device taken on a plane at right angles to that of Fig. 1.

Fig. 3 is a vertical cross section on line 75 3—3 of Fig. 1, showing also a section of a rail.

Fig. 4 is a cross section on line 4—4 of Fig. 1; and

Fig. 5 is a cross section on line 5—5 of 80 Fig. 1.

In the several figures the same reference numerals are employed to indicate corresponding parts.

The operative parts of the mechanism are 85 contained in an elongated cylindrical non-magnetic casing 1 which is designed to be supported by the projections or ears 2 from the equalizer of a car truck in close proximity to the track rail and between the two adjacent car wheels. As shown in Fig. 5, the casing is designed to occupy at least as little, and preferably slightly less, space laterally than the car wheels 3 with which it may be associated.

Within this casing 1 are two coils 4, 4 wound on a brass tube 5 to the opposite ends of which are secured preferably by screw threads, semi-circular non-magnetic supports 6 which rest upon pads or shoulders 7 at ends of the main body portion of the cylindrical casing. Through the center of the brass tube 5 extends a steel shaft or rod 8 into the ends of which are set brass or non-magnetic extensions 9 that at the 90 right hand end being hollowed out to permit the passage of controlling wires 10.

The extreme ends of the brass extensions 9 carry the inner race ways of ball bearings 11, which are mounted in the semi-circular 110

end supports 6, so that the coils and the central shaft or rod 8 constitute a single unitary structure which may be inserted or removed as a whole from the casing. When 5 inserted, plugs 12 of suitable shape are inserted and secured in the open ends of the supports 6 and into these are passed screws 13 which hold end caps 14 in place and thus form a watertight casing or housing for the 10 device.

Between the brass tube 5 and the central steel shaft 8 is a steel tube 15 to the ends of which are secured steel L-shaped members 16 which constitute feet and extending at 15 right angles from these feet and fastened by screws thereto are light non-magnetic parts 17 the ends of which carry the outer members of ball bearings 18, the inner race ways of which are secured to the extensions 9 of 20 the central steel shaft 8. Counter-balancing weights 19 for the feet 16 are secured to the member 17. By this construction the steel tube 15 and its attached parts are free to turn in ball bearings 18 while the shaft 8 is 25 free to turn in ball bearings 11, but as will be seen the movements of these parts are limited so as to amount to merely an oscillation, and the shaft as well as the tube, as will be shown, are balanced in these 30 bearings.

The steel portion of the central rod 8 extends out beyond the ends of the steel tube 15 and to such portions are secured L-shaped feet 20 similar to feet 16, but extending in 35 opposite directions, as shown in Fig. 1, and to the upper part of the said feet are secured counter-weights 21. The two counter-weights, as shown in Fig. 2, interlock, and therefore act as stops to limit the motion of 40 the feet secured to the steel shaft and tube in their downward direction which tends to bring them into the same vertical plane. In all relative positions which they are capable of assuming, however, the feet are free to 45 turn on the bearings 11, therefore no vibratory motion imparted to the casing has any noticeable tendency to separate these two concentrically mounted members.

At one end of the device are insulated 50 brushes 22 set in the counter-balance 19 and the extension 17, and these bear on a commutator 23, Fig. 4, which is divided into four quadrants, the diametrically opposite quadrants being electrically connected, and the 55 brushes being also electrically connected in multiple, so that the brushes close a circuit through either pair of quadrants upon which they may rest. It is desirable that the insulating spaces between quadrants 60 should be of such width relatively to the brushes that neither of the latter can span two adjacent quadrants in the operation of the device.

When in use current is sent through the 65 coil 4 in such direction as to produce in the

central steel bushing or pole piece 24 and the magnetic insert 25 in the casing upon which it rests a consequent pole, say of plus sign, and at the ends of the magnetic element poles of the opposite, say minus, sign. The 70 feet 16 and 20 therefore, being the same sign, will tend to normally repel each other and to spread apart as shown by the dotted lines in Fig. 4 and the arrangement is such that considering Fig. 4 for example, the foot 16 75 swings to the right and foot 20 to the left. This results in a movement of the brushes in an anti-clockwise direction and of the commutator in a clockwise direction, since the latter moves with the shaft 8 while the 80 brushes move with the steel tube. The maximum displacement of the feet under normal conditions is approximately 90° so that when said feet are in the position shown in Fig. 4 in full lines, one of the circuits 85 through the commutator is closed and the other broken, but when said feet assume the positions shown in dotted lines these circuit conditions are reversed. In either, or in any intermediate position, however, it is 90 manifest that both feet are free to turn about the bearings 11, and still maintain their angle of separation.

In Fig. 3 there are shown two light chains or cords 26, 27, secured to the semi-circular 95 end support and carried around and secured to the central shaft and the steel tube respectively. These act as stops which do not limit the angle of separation of the feet but only the angle of oscillation around bearing 11, and thereby the transmitting of vibratory impulses to the feet and thus affecting adversely the device.

A tube 28 enters the top of the casing 1 105 and through it the necessary circuit wires are passed, and the other details of construction not specifically hereinbefore described will be understood from the statement of operation which follows.

It has been stated that the device is supported between the wheels of a truck in close 110 and fixed proximity to a track rail 29. An electric current is passed to coils 4 by wires 30, 31, and a consequent pole established in the pole piece 24 and its extension in the magnetic insert 25, the polarity at the free 115 ends of the coils being of opposite sign. The magnetic path is therefore from the center to each end and back through the rail to the insert 25. Under this influence the similarly magnetized feet mechanically balanced and free to move will repel each other and assume the positions shown in dotted lines in Fig. 4. The feet will be assisted in holding this position by placing a magnetic bar 32 against the central pole piece 24 and will remain floating, as it were, without causing any tension on the stop chains 26, 27. In 120 this way a fixed position relatively to the stationary parts, as well as to each other, is 125 130

assumed by the feet 16 and 20, which is moreover free from all effects of vibrating action.

Assume, however, that a mass of magnetic iron be brought beneath the ends of the separated feet, they will in moving toward such mass, swing together, and will follow the mass if it be moved laterally, within the limits imposed by the chain stops, without 10 spreading or separating and thereby operating the circuit controlling brushes and commutators. This would be the condition imposed by the passage of the device over a magnetic rail. Under these circumstances 15 the two similarly magnetized feet may and practically do not assume a true vertical position, but the center of their combined mass tends to follow the mass of the rail and if a similarly magnetized portion of the rail is 20 presented to them so that they are suddenly subjected to a repulsive effect, they will always move apart and operate the circuit controller whatever may be their position.

The length of the device and the distance 25 between the two pairs of feet result in marked advantages in operation, as the frequently encountered breaks in the magnetic continuity of the rails occurring at switches and elsewhere, may be passed without affecting the magnetic elements, since one magnetic path is preserved unbroken while the other may be affected by the passing gap.

Structurally, in other respects, this device marks a long advance in the art. The dimensions of the controller casing render it 35 possible to fully protect it from stationary obstacles along the right of way. The moving elements have less mass than any others, of which we are aware, designed for accomplishing the same results. The action is quick and sure, and of such nature that the device may be applied and utilized in many ways and in various systems now known in the art.

With the method of use of this apparatus the present application is not directly concerned. It is manifest that the movement of the feet and operation of the circuit controller, for whatever purpose it may be intended, is secured by using at one or more points along the right of way, non-magnetic sections of rail, or by magnetizing rail sections so that they will exert a repulsive, instead of an attractive, effect upon the feet. For this means for control the apparatus is 50 peculiarly well adapted, as the passage of the device over a section of rail having the same magnetic polarity as the feet will cause the latter to separate instantly and positively. These are all matters which are now known in the art, and further explanation thereof is not necessary herein.

What we claim as our invention is:—

1. In a controlling device for railroad operation, the combination with an elongated

non-magnetic casing adapted to be suspended from a car in close proximity to a track rail of two coils wound to produce a consequent pole at the center and two movable magnetic armature elements at each 70 end of the casing of like polarity which is of opposite sign to that of the consequent pole, and adapted to be moved toward or away from the rail according to the magnetic condition of the latter. 75

2. In a controlling device for railroad operation, the combination with an elongated non-magnetic casing adapted to be suspended from a car in close proximity to a track rail, of two coils wound to produce a consequent pole at the center, and two pairs of movable magnetic armature elements at its ends of like polarity opposite to that of the consequent pole and adapted to be moved toward and away from each other according 80 to the magnetic condition of the rail over which they pass. 85

3. In a controlling device for railroad operation, the combination with an elongated non-magnetic casing adapted to be suspended from a car in close proximity to a track rail, of two coils therein wound to produce a consequent magnetic pole at the center and two like poles of opposite sign at 90 its ends, two pairs of rotatably movable armature elements at the ends, normally repelled and spread apart by repulsion but adapted to be drawn together when passing over a magnetic rail, and a circuit controller operated by their movements. 95

4. In a device of the kind described, the combination with an elongated non-magnetic casing adapted to be suspended from a car in close proximity to a track rail, of coils therein wound to produce a consequent magnetic pole at the center, a magnetic shaft and a magnetic tube extending through the coils and each mounted to turn freely in longitudinal bearings, two pairs of magnetic armature elements secured to the tube 100 and to the shaft respectively and a circuit controller operated by the movement of said elements away from a vertical plane due to repulsion and toward a vertical plane due to the force of attraction of the magnetic 105 rail. 110

5. In a device of the kind described, the combination with the elongated non-magnetic casing adapted to be suspended from a car in close proximity to a track rail, of two coils thereon wound to produce a consequent pole at the center, a solid magnetic shaft and a concentric magnetic tube extending through the coils and independently mounted to turn freely in longitudinal bearings, a 120 pair of magnetic feet at the ends of the coils, one of each pair being secured to the shaft and the other to the tube, and a circuit controller operated by the separation of the feet 125 on opposite sides of the vertical due to re- 130

pulsion and the approach of said feet due to the attractive effect of a magnetic rail.

6. In a device of the kind described, the combination with an elongated non-magnetic casing adapted to be suspended from a car in close proximity to a track rail, of two coils therein wound to produce a consequent pole at the center, a magnetic rod or bar and a concentric magnetic tube extending 10 through the coils, and independently mounted so as to turn freely about a horizontal axis, two magnetic feet secured to the ends of the rod and two similar feet secured to the ends of the tube, balance weights connected 15 with or carried by the feet and a circuit controller operated by the spreading movement of each pair of feet due to repulsion, and their approach due to the attractive effect therefor of a magnetic rail.
- 20 7. In a controller of the kind herein described, the combination with the non-magnetic elongated casing of two coils wound to produce a consequent pole at the center and poles at the ends of opposite sign thereto, of 25 two concentric magnetic core supports extending through the coils and independently mounted so as to turn freely about a

longitudinal axis, two pairs of feet secured to the ends of the core supports respectively, interlocking counter-balance weights carried 30 by the feet, and serving as stops to limit the movement of approach of said feet, and a circuit controller operated by the movements of the feet due to repulsion and attraction to an outside mass of magnetic material. 35

8. In a controller of the kind herein described, the combination with an elongated non-magnetic casing of a magnetic element constructed as a single unitary structure 40 adapted to be inserted in or removed from the casing and comprising two coils wound to produce a consequent pole at the center, non-magnetic end supports to which said coils are secured, armatures secured to concentric independently rotatable core supports extending through the coils, and adapted to be moved by repulsive and attractive magnetic force. 45

In testimony whereof we hereunto affix 50 our signatures.

AUSTEN H. FOX.
ARNOLD W. LENDEROTH.
